UNITED STATES PATENT OFFICE.

WILLIAM H. DAY, OF EAST HAVEN, CONNECTICUT, ASSIGNOR, BY MESNE ASSIGNMENTS, TO REMINGTON RAND INC., OF NEW YORK, N. Y., A CORPORATION OF DELAWARE.

INDEX OR FILE.

Application filed November 19, 1924. Serial No. 750,791.

This invention relates to indexes or files, and more particularly to that class of indexes wherein a plurality of index cards or members are arranged in series upon a holder, in overlapped relation with each other, whereby a marginal edge of each is exposed to view.

Preferably such cards are slidably mounted upon a holding device, and should be adapted to be readily separated from each other, as well as easily engaged by and readily released from the holder. Means may also be provided whereby one card supports another of the series, preferably the underlying one. Arrangements for nesting the individual cards with the card next above or below, are a convenience in some instances, and when nested, it is desirable that the cards lie flatwise upon the support.

One object of this invention is to provide an improved form of index card, which will be adapted to be engaged by and mounted upon a supporting member in such a manner that a plurality of the same may be arranged in overlapping relation with the margin of each exposed to view, and be more readily separated when so mounted and more readily removed from or applied to said supporting member than previously experienced with similar types of cards.

Other objects of this invention are to provide means in combination with index cards of this and similar types, whereby the support engaging portion may be more easily manipulated, whereby an easier movement of the card upon the support or into and out of nested engagement with another card will be obtained, whereby the series of cards will more compactly lie upon the holder and whereby the combined thickness of the cards and holder will be lessened.

To these and other ends, the invention consists in the novel features and combination of parts to be hereinafter described and claimed.

In the accompanying drawings:

Fig. 1 illustrates one type of holder or frame, with which the novel index card of this invention is adapted for use;

Fig. 2 is a view showing the improved index cards which embody the features of my invention, mounted upon a supporting member which is adaptable for use with the frame shown in Fig. 1, or with other forms

of equipment, the cards being shown in various positions thereon;

Fig. 3 is a plan view of one of the index cards;

Fig. 4 is a section on line 4—4 of Fig. 2;

Fig. 5 is a section on line 5—5 of Fig. 2;

Fig. 6 is plan view of the support engaging portion of a somewhat modified form of improved index card, and,

Fig. 7 is a bottom edge view of the card shown in Fig. 6.

The particular form of index card selected for illustrating this invention is somewhat similar to the index card described and claimed in Patent No. 1,048,056, issued to Irving Fisher, December 24, 1912, and in certain aspects of the invention may be considered an improvement thereof.

The leaf 10 of Fig. 1, illustrates one form of equipment with which index cards of this type may be efficiently used, and is of the swingable class usually insertable between like leaves and being supported in a vertically swinging position, having lateral extending support engaging fingers 11. A retaining strip 12, adapted to engage and hold index cards of this type, is mounted upon this leaf and a plurality of index cards 13 are arranged in series and retained thereby, the cards being adapted, as will be pointed out hereinafter, to lie flatwise upon the support in overlapping nested relation with a margin 14 of each exposed to view.

The retaining strip or supporting member 12, comprises a strip of material, preferably sheet metal, provided with a central portion 15, and oppositely directed horizontally disposed flanged sides 16 and 17, which are raised above the plane of the central portion. The central portion 15 may be secured to the holding frame or device by any suitable means, such as rivets 18. When the supporting member 12 is used with a device, as shown in Fig. 1, a pair of spring fingers 19 and 20 are usually provided to support the series of cards against downward slip- page therefrom.

The index cards 13 are usually formed from a sheet of material, such as cardboard, or the like, and are each provided with a pair of tongues 21 and 22, which are generally cut therefrom by suitably formed dies. The base portion 23 of these tongues is left integral with the card body, while tab por-

tions 24 and 25 are formed on the respective tongues so as to lie in a substantially transverse line across the card and in opposed relation, both being directed inwardly toward the longitudinal center of the card. Previous to this invention, the material below these tab portions was allowed to remain joined to the body of the card at 26, but the principal disadvantage caused thereby was found to be eliminated by the removal of this material, whereby openings 27 and 28 are formed, thereby spacing the inwardly directed tabs 24 and 25 from the margin of the card directly below the same. By this novel arrangement, one advantage obtained consists of the provision of convenient finger holds outlined by the curved line 29, whereby tongues 21 and 22 can be more conveniently depressed in order to insert the tab portions 24 and 25, respectively, beneath the flanged sides 16 and 17 of the supporting member 15. In addition to this advantage, the cards when nested together with the edge of one between the tongues and the rear surface of another, can more easily be separated from each other out of nesting engagement, due to the elimination of the additional friction of the gripping action upon the nested card, caused by the material which previously filled the openings 27 and 28. Another advantage obtained is that the card can be more easily slipped along the supporting strip 12, after having been mounted thereon, which likewise was made possible by the elimination of the friction or gripping action, by the provision of openings at the above described point. Still another advantage obtained by the use of this novel form of card is that the cards may be more readily slipped over the end 29 of the supporting member 12, as shown at the upper portion of Fig. 2, due to the fact that the tab portions 24 and 25 are free at their lower edges and are more exposed for engagement by the flange ends 29, because of the provision of openings therebelow. These advantages all combine to increase the usefulness of the index card by speeding up the operation of filing the cards, either as a new series upon a support or by the addition of others to an already existing index, and by allowing a more rapid inspection or reference thereto by the increased ease of manipulation thereof.

The cards 13 are also caused to lie more flatly upon the supporting member 12 (than previously experienced in this type of card), by the provision of the openings 27 and 28. Previously the material at these points, because of not being positively retained in the plane of the card, was forced upwardly by the underlying nested card, whereby the overlying card was sprung upwardly at the sides thereof. This upward springing action also caused each succeeding card to

stand outwardly away from the other intermediate the sides at the exposed margin thereof. By the provision of the openings 27 and 28, therefore, the cards not only lie more flatly upon the support at the side edges thereof, but each adjacent card also lies more flatly upon the other card, being substantially in contact therewith across the entire superimposed surface area, the action being in this instance, one tending toward side edge depression instead of upward springing.

In order to increase the tendency to lie flatwise upon the support, the addition of the features shown in Figs. 6 and 7, may be provided, and in certain aspects thereof these are also useful when applied to the particular form of cards of the Fisher patent mentioned above, or other forms for like uses, as well as the cards of the present invention. These features comprise the offsetting of the tongues or support engaging portions 21 and 22 rearwardly out of the plane of the body of the card. One arrangement by which this may be accomplished is shown in Figs. 6 and 7, where the portions 30 and 31 of the card, 13, adjacent the connection of the tongues therewith are pressed rearwardly out of the plane of the remainder of the card a sufficient amount to allow the tab portions 24 and 25 of the tongues to more readily engage beneath the flanges 16 and 17 without distorting the remainder of the card. This structure also offsets rearwardly the edges 32 and 33 upon which the underlying nested card edge rests, a sufficient amount, so that said edges lie in substantially the same plane thereof, whereby a more efficient and positive support is produced in substantially the form of an upwardly directed shoulder.

As stated above, the provision of the openings 27 and 28 in the index cards instead of leaving the material of the card therein, which as shown at 35, is directly above the high points or flanges 16 and 17 of the support 12, the upwardly springing action of the center portion of the cards of the series is avoided and, therefore, when a large number of leaves 10 are arranged in juxtaposed position less space is required in cross section of the combined leaf and contained cards before there is interference or contact between the opposed cards of adjacent leaves. This obviously allows a larger number of leaves to be used within a given lateral space and so increases the data containing area of the whole unit of index equipment.

It will, of course, be understood that while the above description is based upon the particular card shown and the position of the same upon a support which, in this instance, is generally termed "upstanding", that the features above noted may also be embodied in the so-called downhanging

card with equal results to obtain the advantages noted.

While I have shown and described a preferred embodiment of my invention, it will be understood that the same is not limited thereto in all of its details, but is capable of many modifications and variations which will fall within the spirit of the invention and the scope of the appended claims.

10. What I claim is:

1. In an index or file, an index card having a pair of tongues projecting inwardly from a marginal portion thereof, each of said tongues having a transversely directed tab portion, substantially in parallelism with said marginal portion, the portion of said card being removed below said tab whereby said tab is spaced from said margin.

15. 2. In an index or file, a card-retaining strip adapted to present a pair of outwardly directed flanges, an index card mounted thereon, said card being provided with a pair of tongues struck therefrom and adjacent a marginal portion thereof, said tongues having inwardly directed tab portions for engagement beneath said flanges, said tabs being spaced from said marginal portion to provide openings between said tabs and said marginal portion through which said tongue may be readily manipulated to insert said tabs beneath said flanges.

3. In an index or file, a card-retaining strip adapted to present a pair of outwardly directed flanges, an index card mounted thereon, said card being provided with a pair of tongues struck therefrom and adjacent a marginal portion thereof, said tongues having inwardly directed tab portions for engagement beneath said flanges, said tabs being spaced from said marginal portion to provide openings between said tabs and said marginal portion through which said flanges may readily be inserted to engage said tab portions.

45. 4. In an index or file, a card-retaining strip adapted to present a pair of outwardly directed flanges, an index card slidably mounted thereon, said card being provided with a pair of tongues struck therefrom and adjacent a marginal portion thereof, said tongues having inwardly directed tab portions for engagement beneath said flanges, said tabs being spaced from said marginal portion to provide openings between said tabs and said marginal portion and co-extensive with said tabs through which said flanges may readily slide when in engagement with said tabs.

60. 5. In an index or file, a frame provided with a card-retaining strip having outwardly directed flanges at both edges thereof, a series of index cards mounted thereon in nested overlapped relation, each of said cards being provided with a pair of tongues struck therefrom and adjacent a marginal

portion thereof, said tongues having inwardly directed tab portions for engagement beneath said flanges, one of said cards being nested between the tongue and body of another card, said tab being spaced from said marginal portion to provide openings between said tabs and said marginal portion and coextensive with said tabs therebetween through which said flanges may be readily inserted, whereby said series of cards may readily slide thereon.

6. In an index or file, a frame provided with a card-retaining strip having an outwardly directed flange at an edge thereof, a series of index cards mounted thereon in nested overlapped relation, each of said cards being provided with a tongue struck therefrom and adjacent a marginal portion thereof, said tongue having an inwardly directed tab portion for engagement beneath said flange, one of said cards being nested between the tongue and body of another card, said tab being spaced from said marginal portion to provide an opening between said tabs and said marginal portion and coextensive with said tabs through which said flange may be readily inserted, whereby said series of cards may readily slide thereon.

7. In an index or file, a card-retaining strip provided with outwardly directed flanges, an index card slidably mounted thereon having a pair of tongues provided with inwardly directed tab portions to engage beneath said flanges, said tongues being connected to said card adjacent a marginal portion thereof, said tab portions being spaced above the connecting point of said tongues with the marginal portion of said card, whereby an opening coextensive with said tab portions is formed therebetween.

8. In an index or file, an index card having oppositely directed tongues struck therefrom and joined to a marginal portion of said card, said tongues and the marginal portion joined thereto being offset rearwardly beyond the plane of said card.

9. In an index or file, an index card provided with a tongue directed inwardly from a marginal portion thereof, said tongue being connected at its base to said marginal portion and with said marginal portion offset from the plane of the surface of said card.

10. In an index or file, an index card provided with a pair of tongues connected to a marginal portion of said card, said tongues having tab portions projecting toward each other, said tongues and part of said marginal portion being depressed below the surface of said card.

11. In an index or file, an index card provided with a pair of tongues connected to a marginal portion of said card and having tab portions projecting toward each other,

said tongues and part of said marginal portion being depressed below the surface of said card, said tabs being spaced from said marginal portion of said card by an opening 5 formed by the removal of the portion of said card lying between said tab and marginal portion thereof.

12. In an index or file, an index card provided with a tongue directed inwardly from 10 the lower marginal portion thereof, and an upwardly directed shoulder extending parallel with said marginal portion to one side of the connecting point between said tongue and said card.

13. In an index or file, an index card provided with a tongue directed inwardly from 15 the lower marginal portion thereof, and an upwardly directed shoulder extending parallel with said marginal portion to one side 20 of the connecting point between said tongue and said card, said shoulder being offset from the plane of said card.

14. In an index or file, an index card provided with a struck-out tongue joined to and 25 directed inwardly from a marginal portion of said card, said tongue and the portion of the margin of said card included within the portion of said tongue at the juncture thereof with the marginal portion being depressed 30 below the plane of said card.

15. In an index or file, an index card comprising a strip of material having a portion adjacent the lower marginal portion thereof struck therefrom to form a tongue, said tongue being joined to and directed upwardly from 35 said marginal portion, a portion of the margin of said card at each side of said tongue being separated from said card and offset from the plane of said card to form an upwardly directed shoulder at each 40 side of said tongue.

16. In an index or file, an index card comprising a strip of material having a portion adjacent the lower marginal portion thereof struck therefrom to form a tongue, said 45 tongue being joined to and directed upwardly from said marginal portion, a portion of the margin of said card at each side of said tongue being separated from said card and offset from the plane of said card to form 50 an upwardly directed shoulder at each side of said tongue, said tongue having a tab portion directed substantially parallel to the marginal portion of said card and spaced from one of said shoulders by the removal 55 of the material forming said card lying therebetween.

In witness whereof, I have hereunto set my hand this 17th day of November, 1924.

WILLIAM H. DAY.

CERTIFICATE OF CORRECTION.

Patent No. 1,675,331.

Granted July 3, 1928, to

WILLIAM H. DAY.

It is hereby certified that error appears in the printed specification of the above numbered patent requiring correction as follows: Page 2, line 5, for the word "car" read "card"; page 3, line 18, claim 1, for the word "margin" read "marginal portion"; line 22, claim 2, for the word "cards" read "card"; line 69, claim 5, for "tongue" read "tongues"; line 70, for "tab" read "tabs" and line 73, strike out the word "therebetween"; and that said Letters Patent should be read with these corrections therein that the same may conform to the record of the case in the Patent Office.

Signed and sealed this 28th day of August, A. D. 1928.

M. J. Moore,
Acting Commissioner of Patents.

DISCLAIMER

1,675,331.—*William H. Day*, East Haven, Conn. INDEX OR FILE. Patent dated July 3, 1928. Disclaimer filed November 18, 1929, by the assignee by mesne assignments, *Remington Rand Inc.*

Hereby enters this disclaimer to that part of the claim in said specification which is in the following words, to wit:

“12. In an index or file, an index card provided with a tongue directed inwardly from the lower marginal portion thereof, and an upwardly directed shoulder extending parallel with said marginal portion to one side of the connecting point between said tongue and said card.”

[*Official Gazette December 3, 1929.*]
